UNITED STATES PATENT OFFICE.

VIRGIL P. CRAMER, OF ELYRIA, OHIO.

DESIGN FOR A SAVINGS-BANK.

46,201.

Specification for Design.

Patented Aug. 4, 1914.

Application filed April 29, 1914. Serial No. 835,320. Term of patent 14 years.

To all whom it may concern:

Be it known that I, VIRGIL P. CRAMER, a citizen of the United States, residing at Elyria, in the county of Lorain and State of Ohio, have invented a new, original, and ornamental Design for Savings-Banks, of which the following is a specification, reference being had to the accompanying drawing, forming a part thereof.

The figure is a perspective view of a savings bank, shown my new design.

I claim:

The ornamental design for a saving bank, as shown.

V. P. CRAMER.
